UNITED STATES PATENT OFFICE.

TEOFRON BOBERG, OF CLAPHAM PARK, LONDON, ENGLAND, ASSIGNOR TO TECHNO-CHEMICAL LABORATORIES, LIMITED, OF CLAPHAM PARK, LONDON, ENGLAND.

DRYING PROCESS AND APPARATUS.

Application filed May 18, 1920. Serial No. 382,521.

To all whom it may concern:

Be it known that I, TEOFRON BOBERG, a subject of the King of Great Britain and Ireland, and residing at "Fairlawn," Clarence Road, Clapham Park, London, S. W. 4, England, have invented certain new and useful Improvements in or Relating to Drying Processes and Apparatus, of which the following is a specification.

10 This invention relates to the drying of material comprising solid matter in combination or admixture with liquid, say for example, peat pulp.

In co-pending application Serial No. 358,088 there is described a method of drying material of a high water content in two or more stages by means of a revolving drum headed by the evolved vapour after its temperature has been raised a few degrees by compression, the drum being arranged first to pick up a thin layer of the moist material on its circumferential surface and then to transfer it in a partially dried state to other apparatus having similarly heated drying surfaces, the capacity and arrangement of which is sufficient to reduce still further the water content of the material before its final removal therefrom.

It has also been proposed in various prior 30 specifications to dry peat pulp from a water content in the neighborhood of 94% down to a water content, say, of some 10% or less in two or more stages, by various methods, said methods for example comprising filter pressing, band pressing and conveyance in contact with or in suspension in a heated gaseous medium.

The object of the present invention is to combine advantageous features of the foregoing proposals.

The invention consists in a method of drying pulpy or other material having a high liquid content in two or more stages, according to which said material is first 45 treated upon drying surfaces heated by the evolved vapour raised by compression to a higher temperature, and is then further dried during conveyance or suspension in a moving heated gaseous medium.

50 The invention further consists in a method according to the preceding paragraph in which material of high water content, say for example peat pulp, is first deposited as a thin layer upon a surface heated by the

evolved vapour after its temperature has 55 been raised, a small amount by compression, and the resulting partially dried matter is brought to any further desired degree of dryness, while in suspension in hot flue gases or the like in motion in conveying 60 tubes or like conduits.

The invention also consists in improved methods of, or the combination of apparatus for drying material of high liquid content as hereinafter described.

65 The accompanying diagrammatic drawings illustrate some convenient sets of appliances for carrying the invention into effect. In these drawings:

70 Figure 1 shows a complete installation with a screw conveyor for moving the material in the second stage, and

75 Figures 2 and 3 show another known form of apparatus for conducting the second stage.

75 In accordance with this invention when operated in one convenient form, raw peat at ordinary temperature and having a water content in the neighbourhood of 94% is delivered as described in my co-pending application No. 358,088 by a suitable pump *a* through a surface contact heat interchanger *b* heated by water and a surface contact heat interchanger *c* heated by steam into a direct contact heater *d* from which 80 it passes to a trough *e* by means of which it is applied to the surface of a drum *f* rotating in a sealed casing *g*.

Within the casing *g* and adjacent to the trough *e* is a second overflow trough *t* for 90 collecting any wet pulp which may fall from the drum and for returning it, together with a constant overflow from the trough *e*, by means of the pump *u* into the direct contact heater *d* to maintain by circulation a uniform condition of the pulp in the trough *e*.

95 Into the interior of the drum *f* steam, say at a temperature of about 105° C. is delivered by a compressor *h* which draws 100 the steam evolved on the outer surface of the drum *f* at about 100° C. from the casing *g* and raises its temperature by the necessary small amount of, say, 5° C. by compression.

105 Within the casing *g* in contact with the downwardly moving side of the drum *f* are scrapers *i* which remove the more or less

dried matter from the surface of the drum prior to its re-entering the trough *e* and deliver it by means of a collecting hopper *j* to the second stage of the process as herein-after more fully described.

Power for the installation is conveniently derived from a boiler *n* supplying steam, say at 20 kilogrammes per square centimetre and 216° C. which is further heated in the 10 superheater *o* to a temperature of 360° C. and then passes to a turbine *p* for supplying power to the installation, a connection *q* controlled by the valve *q'* from one stage of the turbine conveying steam at 10 kilogrammes per square centimetre and 266° C. 15 to the cylinder *r* of a briquetting press *m*, the exhaust from which at a temperature of 105° C. may also be carried to the drum *f*. A further supply pipe *s* with valve *s'* is 20 also taken from a lower stage in the turbine to supply steam at 105° C. to the drum *f* when required for starting, make up or other purposes.

The condensed water from the drum *f* 25 passes by a connection *v* and steam trap *v'* to the hot water heater *b* from which it is finally rejected at a temperature, say in the neighbourhood of 20° C. after heating the raw peat. The condensed steam from the 30 steam heater *c* also passes by way of the connection *w* and steam trap *w'* to the water heater *b*.

Steam at 105° C. may be taken from the drum *f* by means of a connection *x* to the 35 surface contact steam heater *c*, and any steam not condensed therein may, under control of the valve *y* be returned through the connection *z* and be further utilized in the direct contact heater *d* from which it is 40 finally rejected through the pipe *l*, say at a temperature of 92° C. for the purpose of removing the air and fixed gases, the peat after passage through the hot water heater *b* and surface contact heater *c* being delivered 45 to the direct contact heater *d* at a temperature of about 90° C. and passing therefrom by the connection *3* into the trough *e* at a temperature of 100° C.

A layer or film of the peat pulp is taken 50 up by the surface of the drum *f* as it moves through the pulp in the trough *e* and said film remains closely adhering to the surface as the vapour is driven off and until the more or less dried solid matter is removed 55 by the scrapers *i*.

In the specification of patent No. 1,501,513, July 15, 1924 partially dried material removed from a drum passes to a second stage comprising further evaporating surfaces heated by compressed vapour, but in certain industries, and particularly in the utilization of peat, a supply of heating medium is often available in the shape of flue gases from boiler or other furnaces or exhaust gases 60 from gas engines or the like.

Further, the vapour derived from the evaporation of the pulp may be desirable for other purposes, say for example for use in ammonia recovery producer gas plants as described in British Patent No. 12,013 of 70 1910. For the foregoing and other possible reasons it is proposed in accordance with the present invention to complete the drying by other known methods.

According to the present invention partially dried sub-divided matter resulting from the first drying stage is, in the known manner, fed into a current of hot flue gases, say for example as described in British 75 patent specifications Nos. 16,958 and 24,748 of 1911 and 17,426 of 1912, the drying being carried to any desired degree of completeness in one or more stages, and in accordance with the use to which the dried material 80 is to be put.

When the second stage is to be effected during conveyance as shown in Figure 1, the material entering the hopper *j* is transferred into an extended conveyor conduit *k* in the lower portion of which there is positioned a rotating helix or screw *k'* which carries the more or less powdered material 85 along the conduit in contact with the flue gases from the boiler *n* and superheater *o*, said gases entering by the pipe *o'* and passing along the upper portion of the conduit which they leave by the pipe *o''*.

The screw *k'* keeps the material in a disturbed condition during its passage along the conduit *k*, and thus the heated flue gases come into intimate contact with all the particles and effect a very thorough drying.

The material which may enter the conduit with a water content, say in the neighbourhood of about 30%, may be dried by the hot 90 gases down to a water content, say of about 9%, in which condition it may be delivered to the hopper *m'* of the briquetting press *m*.

In another way of carrying out the invention, the material from the hopper *j* may enter through any suitable proportion device, the connection *4* of a flue *5* through which gases from a boiler furnace or other source are drawn by means of an exhauster 105 *6*. The exhauster delivers the gas in which the more or less powdered material is now suspended into an extended pipe or conduit *7*, from whence it is delivered to cyclone separating devices *8* positioned over the hopper or collecting bin *9* of a briquetting press or any other convenient appliance. This arrangement is similar to that described 110 in British Patent No. 24,748 of 1911, and if desired the powdered material may be treated in two lengths of conduit with return of the partly cooled gases as described in British Patent No. 17,426 of 1912.

Material for treatment in suspension in a current of heated medium may be dried to any suitable water content which will permit 115 120 125 130

- the material to assume a powdered or dis-
integrated condition, and in the treatment
of peat it has been found convenient to dry
the material to a water content in the
neighbourhood of from 30% before remov-
ing it from the drying drum and delivering
it to the hopper 7, and to then complete the
drying from this point down, say, to about
9% before delivering it to the hopper 9.
- 10 It is to be understood that the drum ap-
paratus hereinbefore indicated may be re-
placed by any other suitable apparatus
for carrying out the vapour compres-
sion method of evaporating drying, also
15 that other means may be adopted for com-
pleting the second stage of the process by
drying during conveyance or suspension in
a heated moving gaseous medium, and that
either stage may if desirable be conducted in
20 two or more types of apparatus.

Other additions and modifications may
also be made without in any way departing
from the spirit of this invention.

Having now described my invention, what
25 I claim as new and desire to secure by Letters Patent is:—

1. A method of drying material to be used
for industrial purposes in stages by energy
generated from the combustion of fuel, con-
30 sisting in generating products of combus-
tion, evolving vapour from the moist ma-
terial upon a drying surface, utilizing part
of the energy of said products of combus-
tion to raise the temperature of said vapour
35 by compression, heating the drying surface
by applying said compressed vapour thereto
and removing partly dried material from
said drying surface, and mingling it with
products of combustion of which part of
40 the energy has been already utilized in order
to complete the drying operation.

2. Apparatus for drying material in
stages by energy generated from the com-
bustion of fuel, comprising in combination
45 means for generating products of combus-
tion, means for converting part of the heat
of said products into mechanical work, a
heat transmitting partition, one side of
50 which constitutes a drying surface, means
for utilizing said mechanical work to draw
off vapour generated upon the drying sur-
face and after raising its temperature by
compression returning it as heating medium
55 to the other side of the partition, a con-
duit along which the products of combus-
tion pass after conversion of part of their
heat into mechanical work and means for
removing partly dried material from the
60 drying surface and introducing it into said
conduit to complete a further stage of the
drying by the heat of said products of com-
bustion.

3. Apparatus for drying material in
stages by the energy generated from the
65 combustion of fuel, comprising in combina-

tion a furnace for heating a boiler which
supplies steam, an enclosed drying drum,
means operated by said steam for with-
drawing the vapour evolved on the exterior
of the drum and returning it at a higher
70 temperature and pressure to the interior
thereof, a conduit along which flue gases
pass from said boiler and means for remov-
ing the matter treated upon the drum drier
and mingling it with the flue gases to effect
75 a further stage of the drying operation.

4. A concentration and drying apparatus
for reutilization of latent heat comprising
a fuel combustion apparatus a moving heat
transmitting partition, means for applying
80 to one side of said partition an adhesive
film of heated material, means for collect-
ing the vapor given off by said heated ma-
terial and for raising the temperature of
said vapor by compression and returning it
85 as the heating medium to the other side
of said partition, and means to separate the
material from said partition and mix it
with the products of combustion from said
fuel combustion apparatus.

5. A concentration and drying apparatus
for expelling vapor from material by the
reutilization of latent heat, comprising a
fuel combustion apparatus a moving heat
transmitting partition, means for pressing
95 the film of material onto one surface of
said partition to cause it to adhere thereto,
means for collecting the vapor given off
by the said film of material and for raising
the temperature of said vapor by com-
100 pression and returning it as a heating me-
dium to the other side of said partition,
and means to separate the material from
said partition and mix it with the prod-
ucts of combustion from said fuel combus-
105 tion apparatus.

6. A method of drying material used for
industrial purposes in a plurality of stages
by energy obtained from the combustion
of fuel consisting in utilizing a portion of
heat given off by the combustion to produce
110 mechanical work and utilizing the work
for compressing the vapors given off in the
first stages of the drying process, employ-
ing the compressed vapors as a heating
115 medium for one stage of the drying process,
conveying away the partially dried ma-
terial and mixing it with the products of
combustion to effect the later stages of the
drying process.

7. A method of evaporative drying of
peat pulp having a large water content in
a plurality of stages by energy obtained
from the combustion of fuel, consisting in
utilizing a portion of the heat produced by
the combustion to compress the vapors
given off in the first stages of the drying
process, utilizing the compressed vapors to
reduce the water content of the pulp to
about 30%, then mixing the partially dried
130

pulp with the products of combustion to complete the drying down to a water content of approximately 9% or less.

8. A method of evaporative drying of material used for industrial purposes in a plurality of stages by energy obtained by the combustion of fuel which consists in utilizing a part of the energy resulting from the combustion to compress the vapors given off from the material to be dried, utilizing the

compressed vapors to heat the exterior surface of a revolving drum on which surface the material is carried, removing the partially dried material from the drum and mixing it with the products of combustion 15 to further dry the material.

In testimony whereof I have signed my name to this specification.

TEOFRON BOBERG.
